Matthew B. Blish, Oak Park, Ill.

Application July 6, 1953, Serial No. 25,802

Term of patent 14 years

(Cl. D37—3)

To all whom it may concern:

Be it known that I, Matthew B. Blish, a citizen of the United States, residing at Oak Park, in the county of Cook and State of Illinois, have invented a new, original, and ornamental Design for a Key Holder or Similar Article, of which the following is a specification, reference being had to the accompanying drawing, forming a part thereof.

Fig. 1 is a side elevational view showing my new design.

Fig. 2 is an edge elevational view.

Fig. 3 is a side elevational view.

The broken lines are for illustrative purposes only.

I claim:

The ornamental design for a key holder or similar article, substantially as shown and described.

MATTHEW B. BLISH.
